VALVE

James Hansen, Flushing, N. Y., assignor of one-half to Gustav Drews, Brooklyn, N. Y.

Application October 14, 1937, Serial No. 168,883

7 Claims. (Cl. 221—60)

This invention relates to valves in general and more especially to valves or closures for collapsible tubes, such as today are extensively used for carrying shaving cream, tooth paste, paint and the like.

Among the objects of the present invention, it is aimed to provide an improved non-removable closure or valve having a collapsible tube which will produce not only an effective air-tight moistureproof closure but also a neat closure without the untidy extrusion so commonly accompanying the closing of non-removable closures.

These and other features, capabilities and advantages of the present invention will appear from the subjoined detail description of one specific embodiment thereof illustrated in the accompanying drawing in which

Figure 1 is a fragmental side elevation of a tube equipped with a closure constituting the present invention in closed position;

Fig. 2 is a plan of the valve in closed position;

Fig. 3 is a fragmental section on the line 3—3 of Fig. 1;

Fig. 4 is a fragmental side elevation of a tube equipped with the closure constituting the present invention in open position;

Fig. 5 is a plan of the valve in open position;

Fig. 6 is a fragmental section on the line 6—6 of Fig. 4;

Fig. 7 is a side elevation of the valve removed from the tube looking at a wide curved side thereof;

Fig. 8 is a plan of the valve removed from the tube;

Fig. 9 is a side elevation of the valve removed from the tube looking at a narrow side thereof; and

Fig. 10 is a fragmental section of the tube with the valve removed along the line 6—6 of Fig. 4.

In the embodiment shown, there is illustrated a conventional collapsible tube body 1 having a narrow neck 2. The neck 2 has an inwardly extending internal thread 3 and an opening 4 formed in the outer end of the neck 2.

The opening 4 has a semi-circular outer edge 5 in plan view, see Figs. 2 and 5 and an inner interrupted edge having a short radial portion 6 and a downwardly curved portion 7 separated from the radial portion 6 by a shoulder 8, which shoulder 8 is disposed substantially at the axial center of the neck 2 from the interrupted edge formed by the portions 6 and 7. The neck portion 2 is provided with an inclined conical wall 10 forming a continuation of the cylindrical wall 11

55 of the neck 2. The thread 3, see particularly

Figs. 1, 3 and 6, extends substantially parallel with the outer curved edge 5 of the opening 4. In other words, the curved edge 5 is also spiral in conformation, the flange or shoulder 12 formed on the outer end of the neck 2 adjacent to the curved edge 5 cooperating with the thread 3 to form an internal spiral valve seat portion along such edge 5. The inside of the neck 2 is, in the present instance, provided with a shoulder 13 formed at the outer end of the thread 3.

Adjacent the edge 6, the portion 14 of the neck 11 is slightly curled inwardly to form a protective flange cooperating with the wall 10 and flange 12 to complete the valve seat of the valve now to be described.

The valve 16 now to be described, see particularly Figs. 7, 8 and 9 has a thread 17 for cooperation with the thread 3, a washer receiving recess for receiving the washer 18 which has a semi-circular spiral portion 19, see Fig. 8, conforming to the seat portion formed by the semi-circular spiral flange 12. The washer and recess also have an irregular connecting portion consisting of the elements 20 and 21 conforming to the seat portions formed by the shoulder 14 and tapered wall 10 respectively.

The valve 16 also preferably has a stem 22 extending inwardly to facilitate gripping the valve by a tool during the process of assembling the valve seat tube. For operating the valve 16 and also serving as a stop for limiting the opening movement of the same and in turn for anchoring the valve to the tube in non-removable position after having been once assembled. There is provided in the present instance the handle 23 which preferably extends upwardly from the outer face 24 of the valve adjacent to the washer portion 20. This handle 23 may be of any one of several suitable conformations, as an instance, the hook form illustrated.

In the process of assembling, the stem 22 of the valve 16 is preferably gripped by a tool or the like before the handle 23 is secured in place and thereupon the tube 1 passed over the valve and manipulated until the threads 3 and 17 engage. Thereupon, the tube 1 and valve 16 are preferably turned relative to one another until the valve is in closed position and then the handle 23 is secured in position on the valve 16 preferably to extend from the surface 24 adjacent to the washer portion 20 as indicated in Figs. 5 and 8.

From the foregoing, it will appear that particularly as distinguished from the disclosure in Patent No. 2,067,917, the valve is turned to move outwardly into closed position, whereas in the

aforesaid patent, the valve is moved inwardly into closed position. By this difference, certain decided advantages result. As an instance, when the valve is turned outwardly into closed position, it tends to create a vacuum within the body thereby tending to suck the substance surrounding the valve seat into the body and thereby effectively removing the same from the outlet. When the valve moves inwardly into closed position, on the other hand, pressure is created within the body and there is a tendency to extrude a small increment at the final closing movement resulting in an untidy closure in closed position. Of course, advantage is here still taken of the effective air-tight moistureproof closure resulting when the valve seat assumes the spiral shape of the thread anchoring the valve to the body disclosed in the aforesaid patent except that here, the thread and valve seat are the direct reverse of that disclosed in the aforesaid patent.

In addition to the foregoing, in the present instance, the handle forming one locking element of the closure cooperates with the edge of the opening without requiring an additional stop element.

It is obvious that various changes and modifications may be made in the details of construction without departing from the general spirit of the invention as set forth in the appended claims.

I claim:

1. The combination of a body having an opening, an internally inwardly extending thread, and an internal spiral valve seat substantially conforming to said thread, and a valve having a thread and a spiral face conforming to and cooperating with the thread and spiral seat of said body, the valve seat facing inwardly and the spiral face of said valve facing outwardly.
2. The combination of a body having an opening, an internally inwardly extending thread, and an internal spiral valve seat substantially conforming to said thread, and a valve having a thread and a spiral face conforming to and cooperating with the thread and spiral seat of said body, the threads cooperating to enable the valve to recede inwardly from the opening into open position and to move outwardly into closed position.
3. The combination of a body having an opening, an internally inwardly extending thread, and an internal spiral valve seat substantially conforming to said thread, a valve disposed in said body and having a thread and a spiral face conforming to and cooperating with the thread and spiral seat of said body, and a handle secured to said valve and extending out of said opening to be engaged for manipulating said valve and in turn

to cooperate with the edge of the opening to anchor the valve in rotatable but non-removable position.

4. The combination of a body having an opening, and internally inwardly extending thread, and an internal spiral valve seat substantially conforming to said thread, a valve having a thread and a spiral face conforming to and cooperating with the thread and spiral seat of said body, and a stem extending inwardly from said valve to facilitate engagement of the valve during assembly with the body.

5. The combination of a body having a substantially semi-circular opening, an internal thread and an internal spiral valve seat, one edge of the opening being spiral in form, and a shoulder interrupting the other edge, said spiral seat being disposed inwardly and adjacent to said edges, a valve having an external thread cooperating with the thread of said body and an outer face conforming to said valve seat, said threads enabling said valve to turn inwardly away from said valve seat into open position and outwardly into engagement with said valve seat in closed position.

6. The combination of a body having a substantially semi-circular opening, an internal thread and an internal spiral valve seat, one edge of the opening being spiral in form, and a shoulder interrupting the other edge, said spiral seat being disposed inwardly and adjacent to said edges, a valve having an external thread cooperating with the thread of said body and an outer face conforming to said valve seat, said threads enabling said valve to turn inwardly away from said valve seat into open position and outwardly into engagement with said valve seat in closed position, and a handle secured to said valve and extending out of said opening to be engaged for manipulating said valve and in turn to cooperate with the edge of the opening to anchor the valve in rotatable but non-removable position.

7. The combination of a body having a substantially semi-circular opening, an internal thread and an internal spiral valve seat, one edge of the opening being spiral in form, and a shoulder interrupting the other edge, said spiral seat being disposed inwardly and adjacent to said edges, a valve having an external thread cooperating with the thread of said body and an outer face conforming to said valve seat, said threads enabling said valve to turn inwardly away from said valve seat into open position and outwardly into engagement with said valve seat in closed position, and a stem extending inwardly from said valve to facilitate engagement of the valve during assembly with the body.

JAMES HANSEN.
